UNITED STATES PATENT OFFICE.

CHARLES LAWRENCE STOKES, OF LOS ANGELES, CALIFORNIA.

LIQUID-FEED SYSTEM.

Application filed June 12, 1923. Serial No. 644,924.

My invention relates to improvements in liquid fuel systems.

The invention is particularly applicable to the liquid fuel feed system for carburetors 5 of an internal combustion engine of an automobile wherein the liquid fuel supply is at a lower level than the carburetor and at some distance therefrom.

An object of my invention is to provide 10 an improved liquid fuel system.

Another object is to provide liquid fuel systems wherein liquid fuel may be raised from a low level tank and fed to the carburetor under all operating conditions of the 15 carburetor.

My invention is illustrated in the accompanying drawings forming a part of this application in which;

Fig. 1 is a vertical section partly in elevation of my improved liquid feed system applied to an automobile carburetor;

Fig. 2 is a sectional view of a modification of the liquid fuel system;

Fig. 3 is a sectional view of a further 25 modification;

Fig. 4 is a sectional view of another modification;

Fig. 5 is a sectional view of a further modification;

Fig. 6 is a sectional view of another modification;

Fig. 7 is an elevation of a modification of a part of the structure illustrated in Fig. 1; and

Fig. 8 is a horizontal sectional view of the structure illustrated in Fig. 7.

With reference to the drawings, Fig. 1 illustrates a carburetor having an induction passage 2 adapted to be connected to the intake manifold of an internal combustion engine for supplying a mixture of air and fuel thereto. The passage of air and fuel mixture is controlled by butterfly throttle valve 3 which is disposed in the passage 2. A venturi 4 is mounted in passage 2 and closely fits the inner walls of the passage at the upper and lower ends of the venturi but extends away from the walls at its mid portion leaving an annular space 2^a.

A passage 5 is provided for admitting air to the carburetor with which liquid fuel from a nozzle 6 is commingled. The admission of air to the carburetor through passage 5 is responsive to engine suction. Fuel is supplied to nozzle 6 from a float chamber 7 containing a float 8 which regulates in the well-

known manner the passage of liquid fuel thereto from any source.

A passage 9 connects the induction passage 2 above the throttle 3 with the space 2^a below the throttle and a pipe 12 is joined with passage 9 for subjecting a vacuum tank 16 to engine manifold and Venturi throat depression. The opposite end of pipe 12 is connected with the fuel chamber of the vacuum tank. A passage 14 joins pipe 12 with the float chamber 7 in order to apply the same vacuum in the float chamber as is applied to the vacuum tank.

A liquid fuel reservoir 22 constituting the main fuel supply and generally placed at a lower level than the carburetor as at the rear of the vehicle, serves as a fuel supply for the carburetor. The reservoir 22 has an air vent 23 therein so as to subject the interior of the reservoir to atmospheric pressure. The vacuum tank 16 is located at a higher level than the carburetor. An up-flow pipe 18 and a return pipe 25, both of which communicate with a pipe 21 connected with reservoir 22, are placed in vacuum tank 16 for the purpose of passing fuel from the reservoir through tank 16 to the float chamber 7 when the tank is subjected to a depression in pressure.

Up-flow pipe 18, tank 16, and return pipe 25 constitute a liquid circulation loop, such as is described in my Reissue Patent No. 14,701. In the present instance, however, I arrange this loop for circulating liquid fuel to much greater advantage insomuch as wherein the loop of the earlier structure continued from the liquid fuel reservoir to the vacuum tank, in the present instance I dispense with the greater part of one side of the loop by returning the fuel to the up-flow pipe near the tank 16.

While the operation of the structure set forth in my aforesaid patent under certain conditions is perfect, such as when used with stationary engines or in other places where the vacuum tank is not liable to be lowered below the level of the liquid fuel reservoir, the system when used upon an automobile which is passing down a steep down grade permits flooding of the carburetor. I am enabled by my present invention to entirely overcome this possibility and at the same time to simplify and increase the efficiency of the system.

The return pipe 25 is surrounded at its upper end within tank 16, by an annular

- float 17 which serves to operate a valve 19 for opening and closing a port 20 to control the supply of liquid fuel from the reservoir 22. A small metal disc 25^a surrounds valve 19 and serves to guide the valve to prevent undue fluxuations of fuel in pipe 25. A small hole 24 is formed in pipe 25 near its upper end within the tank 16 so that when the system is not in operation the liquid level 5 in tank 16 will fall, thus opening port 20 permitting fuel to rise in pipes 18 and 25 to the level of fuel in the reservoir 22. Thus the circulating loop is ready to start when the engine is again in operation. The opening 10 24 is sufficiently high above the bottom wall of tank 16 to maintain a small supply of liquid fuel to replenish fuel drawn from the float chamber 7, during starting of the engine.
- 15 20 A pipe 27 on the engine side of valve port 20 interconnects up-flow pipe 18 with return pipe 25 to complete the loop and the upper end of pipe 18 is slightly above the liquid level determinable by float 17 as represented at A—A. Splashing of the fuel as it is delivered into tank 16 is prevented by a baffle 26 adjacent the outlet of up-flow pipe 18.
- 25 30 Small air vent holes 29 are provided in pipe 18 and are vertically spaced apart, one of which may be above the static fuel level therein and the other of which may be below the static level. The arrangement of the holes 29 may be best determined by experiment. Pipe 18 is surrounded by a tube 28 to a point above the upmost of the holes 29 in order to prevent splashing of liquid out through holes 29 where it may escape from the system. The purpose of the vent holes 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 which may be applied through pipe 12 to the vacuum tank 16 and through pipe 14 to the float chamber 7.

The supply of liquid fuel through the nozzle 6 responsive to increasing throttle opening is caused by the differential in depression between float chamber 7 and the depression at the throat of venturi 4. The vacuum applied to the upper end of nozzle 6 is greater than that existing in space 2^a because the area of the opening 11 is much less than the cross sectional area of the throat of the venturi 4 and, therefore, the volume of air drawn in through 2^a will not appreciably effect the total volume and velocity of air passing into the induction passage 2 through the venturi.

A modification of the carburetor is shown in Fig. 2 wherein the equalizing pipe 14 is replaced with a pipe 14^a directly connecting the space 2^a with the float chamber 7. In operation the pipe 14^a functions precisely as does the pipe 14.

In Fig. 3 an assembly of the carburetor and vacuum tank 16 as a unit is shown wherein the float chamber 7^a contains all of the elements as illustrated in tank 16 of Fig. 1.

The vacuum applied to chamber 7^a is passed directly from space 2^a through a pipe 14^b. A restriction 14^c at the point of communication between space 2^a and pipe 14^b serves to control the depression in pipe 14^b. The depression in chamber 7^a is governed by a small air vent 14^d in the top wall of the chamber.

In Fig. 4 I have illustrated a further modification wherein the Venturi tube 4 has another and smaller venturi 4^a with its delivery orifice at the throat of the venturi 4. Nozzle 6 delivers fuel to the throat of the smaller venturi 4^a.

In Fig. 5 I have illustrated a modification similar to the form shown in Figs. 1 and 4 wherein control of the depression at the throat of Venturi tube 4^a is controlled by joining space 2^a with the interior and upper end of venturi 4^a by a small tube 11^a.

In Fig. 6 I have illustrated a modification combining the structures illustrated in Figs. 2 and 5 but in which the elements of the vacuum tank 16 are embodied in a float chamber 7^a as in that form shown in Fig. 3.

At times it may be desirable to substitute in place of the up-flow tube 18 a number of small pipes 30 as shown in Figs. 7 and 8 which add considerably to the lifting efficiency where low vacuum is produced. Such a number of pipes may be designed to supply the same volume of fuel as the single pipe 18. Each pipe, however, would have air vent holes 29^a corresponding to the holes 29 in the pipe 18 as illustrated in Fig. 1.

I find that by supplying a depression of 15 inches of gasoline to the vacuum tank 16

that I can elevate fuel from the reservoir 22 into the tank 16 when the upper end of up-flow pipe 18 is 30 inches above the liquid level in the reservoir. Thus I can make a vacuum tank of small size because I can continuously feed the carburetor, even when the vacuum is very low.

It will be noted that my loop circulating pipes 25 and 18 are at a point remote from the fuel reservoir 22 and the loop may be supplied with fuel by a single pipe 21 attached thereto. Under such conditions as where the vacuum tank 16 is never below the liquid level in reservoir 22, float 17 and valve 19 may be dispensed with and the system would operate successfully. The float 17 and valve 19 are merely for the purpose of accommodating the system to changes in the relative position of the apertures such as would occur when the system is used upon an automobile, motorboat or the like.

I claim:

1. In a liquid feed system, the combination with a liquid fuel reservoir of a liquid fuel tank above the reservoir, means to apply a vacuum to the tank, a pipe loop connected to the tank for circulating liquid fuel therethrough, a pipe for conveying liquid fuel from the reservoir to the loop, means depending on the liquid level in the tank for regulating the flow of liquid through the pipe and means for admitting air to the loop below said tank.

2. In a liquid feed system, the combination with a liquid fuel reservoir of a liquid fuel tank above the reservoir, means to apply a vacuum to the tank, a pipe loop connected to the tank for circulating liquid fuel therethrough, a pipe for conveying liquid fuel from the reservoir to the loop, a float in the tank, a valve actuated by the float for cutting off said pipe from said loop and means for admitting air to the loop below said tank.

3. In a liquid feed system, the combination with a liquid fuel reservoir of a liquid fuel tank above the reservoir, a pipe loop connected to the tank for circulating liquid fuel therethrough, a pipe for conveying liquid fuel from the reservoir to the loop, means depending on the liquid level in the tank for regulating the flow of liquid through the pipe, means to admit air to the loop below said tank and means to apply vacuum to the tank for continuously circulating liquid fuel therethrough and continuously withdrawing air and vapors of the liquid fuel therefrom.

4. The combination with an internal combustion engine of a carburetor, a liquid fuel reservoir below the carburetor, means to generate a predetermined minimum vacuum in the carburetor responsive to the engine suction, means to apply said vacuum to a liquid fuel tank for raising fuel thereto from the

- reservoir, means to feed liquid fuel from the tank to the carburetor and means to supply liquid fuel from the reservoir to the tank; said last mentioned means including a pipe 5 loop connected with the tank and distant from the reservoir, a single pipe connecting the reservoir and loop and a valve for closing off said pipe when the liquid fuel in the tank reaches a predetermined level.
- 10 5. In a liquid feed system for an internal combustion engine having a carburetor for supplying liquid fuel and air to said engine, the combination of a fuel tank, a liquid fuel reservoir at a lower level than the tank, 15 means to apply suction to the tank, means to feed liquid fuel from the tank to the carburetor and means to supply liquid fuel from the reservoir to the tank; said last mentioned means including a pipe loop connected 20 to the tank and distant from the reservoir, the loop having an up-flow pipe and a return pipe, a conduit connecting the reservoir and loop, and a valve placed in the loop for controlling said conduit and automatically 25 operated independently of said suction.
6. In a liquid feed system for internal combustion engines, each having a carburetor or for supplying liquid fuel and air to the engine responsive to suction, the combination 30 of a liquid fuel tank, a liquid fuel reservoir at a lower level than the tank, means to apply suction to the tank, means to feed liquid fuel from the tank to the carburetor and means to supply liquid fuel from the reservoir to the tank; said last mentioned means including a pipe loop connected to the tank and distant from the reservoir, the loop having an up-flow pipe and a return pipe, a conduit connecting the reservoir and loop, 35 and a valve placed in the loop for controlling the supply of fuel to said conduit depending on the liquid level in the tank and automatically operated independently of said suction.
- 40 7. In a liquid feed system for internal combustion engines each having a carburetor or for supplying liquid fuel and air to the engine responsive to suction, the combination of a liquid fuel tank, a liquid fuel reservoir at a lower level than the tank, means to apply the engine suction to the tank, means to feed liquid fuel from the tank to the carburetor and means to supply liquid fuel from the reservoir to the tank; said last 45 mentioned means including a pipe loop connected to the tank and distant from the
- reservoir, the loop having an up-flow pipe and a return pipe, a conduit for passing liquid fuel from the reservoir to the loop, and a valve having a stem passing through the 60 return pipe for controlling the flow of liquid fuel through the conduit.
8. In a liquid feed system for internal combustion engines each having a carburetor or for supplying liquid fuel and air to the 65 engine responsive to suction, the combination of a liquid fuel tank, a liquid fuel reservoir at a lower level than the tank, means to apply the engine suction to the tank, means to feed liquid fuel from the tank to the carburetor and means to supply liquid fuel from the reservoir to the tank; said last mentioned means including a pipe loop connected to the tank and distant from the 70 reservoir, the loop having an up-flow pipe and a return pipe, a conduit for passing liquid fuel from the reservoir to the loop, and a valve having a stem passing through the return pipe and means controlled by the level of the fuel in said tank for controlling 75 the flow of liquid fuel through the conduit.
9. In a fuel feeding system for internal combustion engines a fuel reservoir, a fuel tank at a higher level than said reservoir, a conduit between said tank and reservoir, a 80 conduit between said tank and the intake of said engine for transferring fuel from said reservoir to said tank by the engine suction, the upper portion of said conduit having one or more openings in its side wall 85 for the introduction of air, a bypass connecting said tank with said conduit below said openings, and a float-operated valve for controlling the flow of fuel through said conduit.
10. In a fuel feeding system for internal combustion engines, a reservoir for liquid fuel, a liquid fuel tank above the reservoir, means for applying suction of the engine to said tank, a pipe loop connected to said tank, 90 one portion of said loop being provided with small perforations for admitting air thereto, a conduit for conducting fuel to said loop from said reservoir, a valve anterior of said loop for controlling the flow of fuel through 95 said conduit, and means controlled by the height of the fuel in said tank for operating said valve.

Signed at Wilmington, in the county of Los Angeles and State of California, this 110 20th day of March, A. D. 1923.

CHARLES LAWRENCE STOKES.
